assignor to Marjorie Montgomery, Inc., Los
Angeles, Calif., a corporation of California

Application November 26, 1938, Serial No. 242,499

1 Claim. (Cl. 2—78)

This invention relates generally to garments, and more particularly to feminine outer garments for sports wear.

An object of the invention is to provide a feminine outer garment for sport wear which is openable from the top to the bottom thereof at the front and is structurally characterized by an upper shirtwaist portion permanently connected to a lower portion in the form of a pair of shorts having the appearance of an abbreviated divided skirt, all in a manner to obtain the advantages of separate upper and lower garments in an extremely smart, comfortable, one-piece garment having a permanently closed crotch, and enabling the smart style lines of a pleated skirt to be utilized, with the pleats located symmetrically at the front center of the legs, and with one of the pleats completely concealing the opening in that portion of the garment from the waist down, whereby the lower abbreviated skirt portion of the garment will appear as a separate unit distinct from the shirtwaist portion of the garment.

Another object of this invention is to provide a feminine outer garment of the above described character in which the waist thereof is finished with a permanently secured belt-like structure, the ends of which are arranged in symmetrical relationship to the front center of the garment to have the effect of a separate belt, yet be correlated with that pleat which conceals the openable lower portion of the garment in a manner to aid such pleat in its concealing function, whereby to enhance the appearance of the garment while providing the distinct functional advantage of a separate lower garment in a single unitary structure without exposing the openable feature of the lower portion thereof when closed.

Still another object of the invention is to provide a feminine outer garment which embodies an ingenious and novel pleat structure and fly member for the openable lower portion of the garment which is extremely effective as a concealing closure for such lower portion, in a manner to render the closed opening undetectable, and to carry out the smart pleated skirt effect thereof, all while permitting the lower portion to be conveniently opened whenever desired without disturbing the upper portion of the garment.

With these and other objects in view, the invention consists in the combinations and arrangements of elements, as set forth in the following specification and particularly pointed out in the appended claim.

In the accompanying drawings,

Figure 1 is a view of the garment embodying this invention, in front elevation and completely closed;

Figure 2 is a view of the garment in rear elevation and also completely closed;

Figure 3 is a view similar to Figure 1, but showing the lower "shorts" portion of the garment opened and partly folded back to disclose the crotch and fly member;

Figure 4 is an enlarged detail sectional view of a novel pleat and fly structure, taken on the line 4—4 of Figure 1.

Referring specifically to the drawings, the invention in its present embodiment comprises an upper or shirtwaist portion 10 to the lower edge of which is permanently attached by a belt-simulating band 11 the lower or "shorts" portion 12 constructed to have the appearance of an abbreviated divided skirt. The portions 10 and 12 are secured to the top and bottom edges of 20 the belt band 11 by suitable stitching, and the upper portion is openable along the front center thereof at 13 from the neck to the belt 11.

The free ends 14 and 15 of the belt project equal short distances beyond the free vertical edges of the right and left front sections 16 and 17 forming the front of the shirtwaist portion, and stitched to the rear section 18 forming the back of such portion.

The free ends 14 and 15 of the belt 11 thus are adapted to overlap symmetrically at opposite sides of the front center of the shirtwaist portion 10 and are adapted to be secured together by fastening members such as buttons 19, which are symmetrically related to the vertical row of buttons 20 for closing the central opening of the shirtwaist portion from the neck to the belt. In order to aid the buttons in holding the end edges of the belt fully closed, hooks 21 and eyes 22 are secured thereto, as shown in Figure 3.

The lower "shorts" portion 12 which as previously stated is constructed to have the appearance of an abbreviated divided skirt is made up of right and left hand front sections 23 and 24, respectively, stitched to right and left hand pleated rear sections 25 and 26, and coacting to provide a closed crotch 27, as shown in Figure 3.

The shorts portion 12 is openable from the free end 14 of the belt 11 along the front center of the leg (Figure 1), and such opening is adapted to be completely concealed by one of two pleats 28 and 29 symmetrically arranged on the "shorts" portion, as clearly shown in Figure 1.

The pleat 28 is of conventional construction,

whereas the pleat 29, which is operatively related to the aforesaid opening along the leg of the portion 12, is of a novel construction and arrangement. The pleat structure 29 is composed of 5 outer and inner folds 30 and 31 of the material of the portion 12 (Figure 4), and a fly member 32 extending from the free edge of the inner fold 31 and entirely concealed by both folds when the opening of the lower portion is closed, as shown 10 in Figures 1 and 4.

Suitable fastening members, such as a row of buttons 33, adjacent the edge of the opening in the portion 12, are adapted to co-act with button-holes 34 in the flap 35 of the fly member 32, so as 15 to be concealed by the cover flap 36 of the fly member in addition to the pleat 29. Thus when the opening in the portion 12 is completely closed by the buttons 33, the overlapping pleat 29 will completely conceal the opening and fastening 20 means, and will co-act with the other pleat 28 to give to the portion 12 the appearance of a garment separate from the shirtwaist portion 10.

It will, therefore, be manifest that the one-piece feminine outer garment embodying this invention is capable of being smartly styled and yet 25 provides the advantages of separate upper and lower outer garments, by enabling the lower por-

tion 12 to be conveniently opened or closed without disturbing the upper portion 10, or both portions as easily manipulated to remove or put on the garment as desired.

It will also be clear that the buttons 19, 20 and 5 23 are merely one form of fastening member, and that slide fasteners of the "Zipper" type can be substituted therefor, in which case the pleat 29 will function to conceal the slide fastener in the same manner as the row of buttons 23 is concealed.

What is claimed is:

In a feminine outergarment of the type embodying a lower "shorts" portion having the appearance of an abbreviated divided skirt openable along a leg thereof, a pleat structure comprising outer and inner folds of material forming a pleat at one edge of the opening in the leg adapted to overlap the other edge of the opening; and means for closing the opening, including a 15 fly member carried by the inner one of said folds and concealed by the pleat, so as to render the opening invisible when closed, the fly member having an inner flap concealed thereby and adapted to carry portions of separable fastening 20 means.

MARJORIE MONTGOMERY LUTZ.
